U.S. PATENT DOCUMENTS

2,168,314 A 8/1939 Blanks
2,909,893 A 10/1959 Jacques*Primary Examiner* — Katherine Glennon(74) *Attorney, Agent, or Firm* — Ulmer & Berne LLP(57) **CLAIM**

The ornamental design for a watch, as shown and described.

DESCRIPTION

FIG. 1 is a right front perspective view of a watch, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a rear perspective view thereof; and,

FIG. 9 is a left front perspective view thereof.

The broken lines shown in the figures illustrate portions of the watch that form no part of the claimed design.
